UNITED STATES PATENT OFFICE.

JOSEPH F. GRIFFIN, OF TEANECK, NEW JERSEY, ASSIGNOR TO THE SUPERHEATER COMPANY, OF NEW YORK, N. Y.

EXHAUST-STEAM INJECTOR.

Application filed May 15, 1926. Serial No. 109,304.

The present invention relates to injectors, and has specific reference to the type of injector wherein the primary operating fluid is exhaust steam from an engine, supplemented by a small quantity of high pressure live steam, hereinafter referred to as "supplemental steam", and provided with means whereby live steam of reduced pressure, hereinafter referred to as "auxiliary steam", 10 may be used in conjunction with the supplemental steam for operating the injector when exhaust steam is not available.

Injectors of this type as applied to locomotives are ordinarily equipped with control systems by which the high and low pressure live steam, the exhaust steam, and the water supplied to the injector, are controlled from the locomotive cab by means of valves actuated from a common controlling means.

Typical examples of such injectors and control systems are disclosed in U. S. Letters Patents No. 1,351,004, granted March 24, 1925, to M. Hard, et al., and 1,510,999, granted October 7, 1924, to R. D. Metcalfe, et al., and the present invention has for its general object the provision of an improved form of exhaust steam control valve, for use in conjunction with systems of this general nature. To this end, an object of the invention is the provision of positive locking means for holding the exhaust valve in closed position, which means may be thrown out of engagement with the valve so that the latter may be free to move to either closed or open position under the influence of steam pressure alone. A further object of the invention is the provision of means whereby the exhaust valve will be free of the locking means at all times when the injector is being operated with exhaust and supplemental steam. A further object of the invention is the provision of a combined closing and locking means which will permit the closing of the exhaust valve and maintenance thereof in closed position against exhaust steam pressure, by the use of a spring or equivalent means of relatively light strength. A still further object 50 of the invention is the provision of means whereby the exhaust valve will be automatically closed and locked in closed position when the injector is shifted from exhaust steam to auxiliary steam operation. Other

and more detailed objects of the invention will become apparent as the following description of a preferred form of my invention proceeds.

In the accompanying drawings I have shown my invention applied to an injector of the type above referred to and in which Fig. 1 is a vertical central section of the injector; Fig. 2 is a fragmentary section taken on the line 2—2 of Fig. 1; and Fig. 3 is a fragmentary section similar to Fig. 1, showing a slightly modified form of valve control means.

Referring now to Fig. 1, the injector shown is of a known type, in which within the housing 1 there are successively mounted the main low pressure steam nozzle 2, water nozzle or cone 3, secondary steam nozzle 4, combining tube 5, and delivery tube 6. As these elements of the injector are well known in the art and form no part of the present invention, it is not believed necessary that they be described in further detail.

The housing 1 is provided with an exhaust steam inlet 7 communicating with the steam chamber 8, the inlet 7 being controlled by the exhaust valve 9 pivotally supported from the pin 10 by means of the arm 11, to which it is attached by means of the rivet 12, the latter being provided with a rounded projecting head 13. The valve 9, arm 11, and rivet 12 form a fixed assembly (which may be made integral) rotatable about pin 10 as a center, and the exhaust valve will hereinafter be considered as comprising this assembly.

Forward of the exhaust valve, the housing 1 is formed with a boss 14 forming a bearing for the reception of a transversely placed pin 15, which at its opposite end is supported by a removable bearing 16 suitably secured in the housing 1 opposite the boss 14. The pin 15 carries, preferably integrally therewith, a cam element 17, the main cam surface of which consists of an arcuate portion 18 lying on an arc struck from a point 100 slightly above the axis of pin 15 on the line intersecting the axes of pins 10 and 15. The cam surface 18 merges gradually at its lower end into the substantially radial cam surface 19. The position of pin 15 and the 105 radius of the arcuate portion of the cam 18 are such that with the cam in the position shown in Fig. 1, the valve 9 is held in closed

position by the cam surface 18 contacting with the head 13. Furthermore it is particularly to be noted that the axes of pins 10 and 15 are so placed that with the cam in the position shown, a line drawn through the axes of pin 10 and the point of contact between elements 13 and 18 is at right angles to a line drawn through the axes of pin 15 and the point of contact between elements 13 and 18. The reason for this relative placing of the elements will appear more fully hereinafter.

The cam 17 is provided opposite the cam surface 18 with a projecting operating lever 20, by means of which the cam is rotated to either hold the exhaust valve in closed position or to allow it free movement.

The housing 1 is formed with an extension forming a vertical cylinder 21, in which is slidably mounted the piston 22, the latter carrying the piston rod 23, which projects through the web of the housing forming the lower end of cylinder 22 to engage the upper face of the lever 20. The housing 1 is also provided with webs forming a steam passage 24 providing a communication between cylinder 21 and the supplemental or high pressure steam nozzle 25. A steam pipe 26 leading from the injector control apparatus (not shown) communicates with the steam passage 24 and provides high pressure steam for nozzle 25 and the actuation of piston 22.

Directly below cylinder 21 the housing 1 is suitably webbed to form the cylinder 27, in which is slidably mounted the piston 28 carrying the piston rod 29, the latter projecting through the web forming the top of cylinder 27 to engage the lower face of the lever 20 directly opposite the rod 23. A spring 30, located in cylinder 27, tends to force the piston 28 to the upper end of the cylinder and the force exerted by this spring may be varied by means of a suitably threaded adjusting plug 31. The lower end of cylinder 27 is closed by a suitable plug 32.

Forward of cylinder 27 the injector housing 1 is suitably webbed to form a steam passage 33, communicating with the cylinder 27 below piston 28 and also through ports 34 with the steam chamber 8. A steam pipe 35 leading from the control apparatus (not shown) communicates with passage 33 and supplies thereto low pressure auxiliary steam for the operation of the injector and also for the actuation of piston 28.

The operation of the device is as follows: When the injector controls are closed so that neither high nor low pressure live steam is admitted to the injector, the cam 17 is held in the position shown in Fig. 1 by means of the spring 27 acting through piston 28 and rod 29. In this position the exhaust valve 9 is closed and prevents the entrance of ex-

haust steam into the injector in case the engine is running and exhaust steam is present at the inlet 7. When in this position the relative positions of the pins 10 and 15, and the point of contact between the elements 13 and 18 is such that the line of force exerted by exhaust steam pressure on the valve 9 and tending to swing it open about the pivot 10, passes through the axis of pin 15 and it will thus be seen that the cam 17 when in this position forms a lock holding the exhaust valve closed. The cam surface 18 is, as previously noted, slightly off center with respect to the axis of pin 15. A tangent to the arc at the point of contact with head 13 is, therefore, not quite normal to the line of force exerted by the latter. Because of this, pressure exerted by head 13 will tend to rotate the cam in counter clockwise direction, but this tendency is so slight that it is entirely overcome by friction, and the cam acts as a friction held lock preventing the opening of valve 9. The cam surface 18 is offset in order to compensate for wear on the cam surface or the face of valve 9, and to assure the positive seating of the latter as the cam is rotated to closed position.

Assuming that exhaust steam is available and it is desired to operate the injector, high pressure live steam is admitted to the latter through pipe 26 and, as will be readily apparent from an inspection of the figure, the admission of live steam to the passage 24 will force the piston 22 downwardly against the spring 27 and move cam 17 into a position which allows the exhaust valve 9 to be opened by the pressure of the exhaust steam in inlet 7.

When it is desired to operate the injector on live steam, the auxiliary low pressure live steam is admitted through pipe 35 to the passage 33, from which it passes into the steam chamber 8 and also into cylinder 27 below piston 28. In most instances the auxiliary live steam passing into chamber 8 will be sufficient to close the exhaust valve 9 and prevent the escape of live steam through the exhaust passage, but in order to assure the positive closing of the exhaust valve the area of the piston 28 and the tension of spring 30 are fixed so that upon the admission of low pressure steam into cylinder 27, the pressure of the supplemental live steam acting on piston 22 will be overbalanced and the piston 28 forced to the top of cylinder 27 by the combined forces acting on it. This action will rotate cam 17 to the position shown in the figure, placing the exhaust valve in its closed and locked position.

Because of the fact that the exhaust valve 9 when closed and under exhaust steam pressure is prevented by friction from rotating cam 17, the spring 30 holding the cam in closed position may be made comparatively light and consequently the piston 22, which

must overcome the action of spring 30 to open the valve, may also be of comparatively small size.

It will be obvious that the same action as that described could be obtained by admitting the low pressure live steam below piston 22 rather than below piston 28, but the form shown is preferable, as with this arrangement neither the piston 22 nor piston 28 need be a close or packed fit in its respective cylinder. It will be noted that pistons 22 and 28 are provided with annular faces 22^a and 28^a on their lower and upper faces respectively, and these annular faces, or seats, 15 co-operate with the ends of the respective cylinders to provide steam tight joints when steam is admitted behind the pistons. If the low pressure live steam were admitted below piston 22 for the purpose of overcoming 20 the high pressure steam, it would be necessary to pack this piston and with the arrangement shown, this undesirable feature is eliminated.

When the injector is shut off after having 25 been operated with exhaust steam and with exhaust steam still available at the inlet 7, the cam 17 is returned to its closed position from the open position by the spring 30, which, although comparatively light, is able 30 to rotate the cam and close the exhaust valve against the exhaust steam pressure because of the intermittent character of the latter. It will be readily apparent that during the 35 intervals of reduced exhaust steam pressure occurring between exhaust pressure impulses from the engine cylinders, the spring 30 will gradually rotate the cam 17 in a series of steps until the head 13 is in engagement with the arcuate portion 18 of the cam surface, after which the cam may be rotated with 40 comparative ease until valve 9 is forced to its fully closed position.

In Fig. 3 I have illustrated a modified form of valve which is, in general, similar 45 to that shown in Fig. 1, but in which the exhaust valve is positively closed only when the high pressure live steam supply to the injector is shut off. In this form the valve 9' is pivoted at 10' through lever 11' carrying head 13'. A cam 17' having faces 18' and 19' similar to those previously described 50 in connection with Fig. 1, is similarly mounted in the injector housing and is thrown to open position by means of a piston 22' and rod 23' actuated by supplemental high pressure steam. The spring 30' acting on piston 28', mounted in cylinder 27', acts to throw 55 the cam to closed position in exactly the same manner as that heretofore described, but in this case the auxiliary steam passage 33', supplied from pipe 35', is in communication 60 only with the steam chamber 8'.

In this form the general operation of the 65 valve is the same as that previously described with the exception that during live steam

operation of the injector, the cam 17' is held in open position by the action of the high pressure steam on piston 22', and the exhaust steam inlet 7' is closed only by the action of the low pressure live steam in chambers 8' 70 acting to close valve 9'.

If the operating conditions are such that a positive pressure is assured in the chamber 8' at all times when the injector is operating wholly on live steam, satisfactory operation 75 of the injector may be secured with the more simple modified form.

When the injector is shut off, the exhaust valve 9' is closed and locked in closed position by spring 30', in exactly the same manner as in the preferred form.

It is to be understood that the invention is not to be limited to the illustrative embodiments herein disclosed, but is to be considered as including such changes in form as 85 may fall within the spirit and scope of the appended claims.

I claim:

1. In an injector, the combination with an exhaust valve opened by exhaust steam pressure, of a movable element engaging said valve to lock it in closed position, resilient means urging said element to locking position, and means for moving said element out of locking position against the action of said 95 first named means.

2. In an injector, the combination with a pivoted exhaust valve opened by exhaust steam pressure, of a rotatable cam in one position engaging said valve to lock the latter 100 in closed position and in another position permitting said valve to open, a spring acting to force said cam to said first named position, and a fluid actuated piston acting to force 105 said cam to said last named position against the action of said spring.

3. In an injector supplied with exhaust and supplemental steam and having an exhaust valve opened by exhaust steam pressure, a movable element engaging said valve to lock 110 it in closed position and means actuated by the admission of supplemental steam to the injector to move said element out of locking position.

4. In an injector supplied with exhaust and supplemental steam, the combination with a pivoted exhaust valve opened by exhaust steam pressure, of a rotatable cam in one position engaging said valve to lock the latter 115 in closed position and in another position permitting said valve to open, a spring acting to force said cam to said first named position, and a piston actuated by the admission of supplemental steam to the injector acting to force 120 said cam to said last named position against the action of said spring.

5. In an injector supplied with exhaust, supplemental and auxiliary steam and having an exhaust valve opened by exhaust steam pressure, a movable element engaging said 130

- 4
- valve to lock it in closed position, means actuated by the admission of supplemental steam to the injector to move said element out of locking position, and means actuated by the admission of auxiliary steam to the injector to move said element into locking position against the action of said first named means.
6. In an injector supplied with exhaust, 10 supplemental and auxiliary steam, the combination with a pivoted exhaust valve opened by exhaust steam pressure, of a rotatable cam in one position engaging said valve to lock the latter in closed position and in another 15 position permitting said valve to open, a spring acting to force said cam to said first named position, a piston actuated by the admission of supplemental steam to the injector acting to force said cam to said last named 20 position against the action of said spring, and a piston actuated by the admission of auxiliary steam to the injector acting in conjunction with said spring to return said cam to said first named position against the action 25 of said first named piston.
7. In an injector having an exhaust valve opened by exhaust steam pressure, valve actuating means for closing said valve, a movable element interposed between said 30 means and valve, and a mounting for said element, said element being constructed and arranged to transmit the force exerted by said means to said valve to close the latter, and when in closed position to transmit the 35 force exerted thereon by said valve to said mounting.
8. In an injector having an exhaust valve opened by exhaust steam pressure, an element movable from an open to a closed position 40 in the latter of which it engages said valve to hold said valve closed against exhaust steam pressure, said element forming, when in closed position, a locking member capable of independently retaining said 45 valve in closed position against exhaust steam pressure, a spring urging said element to closed position and a fluid pressure actuated piston for moving said element to open position.
- 50 9. In an injector having an exhaust steam valve opened by exhaust steam pressure, a cam element located adjacent said valve and rotatable to close the same, said element comprising a cam surface which, in closed position, is substantially normal to the line of the resultant force exerted by exhaust steam pressure on said valve, whereby the cam element forms a friction held locking member for said valve, and means for moving said element into and out of engagement with 55 said valve.
10. In an injector having an exhaust valve opened by exhaust steam pressure, a rotatable cam element located adjacent said valve, said element comprising a pivot 60 mounted with its axis lying on the line of the resultant force exerted by exhaust steam pressure on said valve and a cam surface lying on an arc the center of which lies on a line intersecting the axes of said valve and cam pivots between the two and adjacent the latter, and means for rotating said element to bring said cam surface into or out of engagement with said valve to close the latter or permit its free opening under the 65 influence of exhaust steam pressure.
11. In an injector, a housing having a high pressure live steam inlet and an exhaust steam inlet, a pivoted flap valve controlling said exhaust steam inlet, a rotatable cam element mounted transversely of said housing and movable between two positions in one of which it engages said valve on the side opposite said inlet to close the valve and in the other of which it permits free 80 movement of the valve, an operating lever on said cam element, a cylinder located in said housing, a piston located in said cylinder, and carrying a rod engaging one side of 85 said lever, a spring located in said cylinder and acting on said piston to close said valve, a second cylinder located in said housing and in communication with said high pressure steam inlet, a piston located in said last named cylinder and carrying a rod 90 engaging the side of said lever opposite said first named rod.
12. In an injector, a housing having high and low pressure live steam inlets and an exhaust steam inlet, a pivoted flap valve controlling said exhaust steam inlet, a rotatable cam element mounted transversely of said housing and movable between two positions in one of which it engages said valve on the side opposite said inlet to close the valve and in the other of which it permits free movement of the valve, an operating lever on 100 said cam element, a cylinder located in said housing, a piston located in said cylinder, and carrying a rod engaging one side of 105 said lever, a spring located in said cylinder and acting on said piston to close said valve, a port providing communication between the portion of the cylinder in which the spring is located and said low pressure live steam 110 inlet, a second cylinder located in said housing and in communication with said high pressure steam inlet, a piston located in said last named cylinder and carrying a rod 115 engaging the side of said lever opposite said first named rod.

JOSEPH F. GRIFFIN.
